THOMAS M. DANIELS, OF CHICAGO, ILLINOIS.

SAFETY CONTROLLING APPARATUS FOR AEROPLANES.

1,153,035.

Specification of Letters Patent. Patented Sept. 7, 1915.

Application filed April 23, 1912. Serial No. 692,602.

To all whom it may concern:

Be it known that I, THOMAS MARION DANIELS, a citizen of the United States, and a resident of Chicago, in the county of Cook 5 and State of Illinois, have invented a new and Improved Safety Controlling Apparatus for Aeroplanes, of which the following is a full, clear, and exact description.

My invention relates to aeroplanes and 10 flying machines analogous thereto, my more particular purpose being to provide means for balancing the machine so that in case the machine is accidentally tilted it will correct its own position, and failing that, its position 15 may be corrected wholly or in part by the operator.

More particularly stated, I provide a machine with propellers having adjustable blades and disposed with their axes normally 20 vertical, but free to swing in planes crossing the general plane of rotation of the propeller blades, and separate mechanisms, one controllable by hand at the will of the operator, and the other controllable automatically 25 by movement of a weight carried by the machine for shifting the positions of the said propellers in order to correct the position of the entire machine.

Reference is to be had to the accompanying 30 drawings forming a part of this specification, in which similar characters of reference indicate corresponding parts in all the figures, and in which—

Figure 1 is a plan view of an aeroplane 35 complete and provided with my improved balancing propellers; Fig. 2 is a substantially vertical longitudinal section through the machine shown in Fig. 1; Fig. 3 is a cross section on the line 3—3 of Fig. 2, looking 40 in the direction of the arrow; Fig. 4 is a detail of one of the propellers provided with adjustable blades and with means whereby the same are adjusted; Fig. 5 is a section on the line 5—5 of Fig. 4, and showing 45 the addition of certain parts; and Fig. 6 is a detail showing the centrally disposed propeller provided with adjustable blades.

At 7 is the general framework sometimes 50 designated as the car body, and at 8 are caster forks in which are journaled wheels 9 by aid whereof the machine may alight without injury. The framework comprises standards 10, 10^a, the standards 10 inclining outwardly from each other at their tops as

will be understood from Fig. 3 and being 55 provided adjacent to their tops with bearings 11, as indicated in said figure. A supporting plane is shown at 12 and is secured to the tops of the standards 10. Mounted upon the under side of the plane 12 and depending therefrom is a hanger 14 carrying a bearing 13. Another hanger 15 is mounted upon the under side of the plane 12, and for this purpose is provided with a foot 16. The hanger 15 carries a bearing 17. A shaft 60 18 extends through the bearing 17 and at its upper end is provided with a bevel gear 19. The shaft 18 is further provided, adjacent to its lower end, with a bevel gear 20. A bearing 21, mounted upon the floor of the 65 car, serves as a support for the lower end of the shaft 18. A bevel gear 22 meshes with the bevel gear 20 and is turned by an engine 23. A fly wheel 24 is associated with the bevel gear 22 and is driven also by the engine 23. 70

Disposed below the supporting plane 12 are two bearings 26, 27, which are in alignment with the bearing 13. A shaft 25 extends through all three of these bearings, 80 and also through a bearing 25^a which is carried upon a standard 10^a immediately at the rear of the engine 23. The shaft 25 carries a propeller 28 which may be of the usual or any desired construction. Mounted 85 rigidly upon the shaft 25 are bevel gears 29, 30, the gear 30 meshing with the bevel gear 19. Meshing with the bevel gear 29 are two other bevel gears 32 mounted respectively 90 upon shafts 33 disposed in line with each other and extending outwardly in opposite directions from the center of the machine.

Each shaft 33 carries at its outer end a bevel gear 34 mounted rigidly upon it. This bevel gear meshes with another bevel gear 95 35 carried by a short shaft 36, the axis of rotation of which is normally vertical. Slidably mounted upon the shaft 36 is a collar 37. A pair of links 38 is pivotally mounted upon the collar 37 and extended obliquely 100 outward in opposite directions, each link 38 being pivotally connected with a propeller blade 39. These propeller blades 39 are each mounted to turn upon its own horizontal axis, or in other words, to change the inclination thereof according to the position of the collar 37 relatively to the ends of the shaft 36 upon which it is movable. The up- 105

per end of the shaft 36 is provided with a square head 40 and extending through this head are pins 40^a by aid whereof the blades are journaled and thus adapted to change 5 their inclination, as stated.

For the purpose of shifting the collar 37 relatively to the shaft 36, I provide a fork 41, this fork being journaled upon a bracket 43 by aid of a pivot pin 42. The fork 41 is 10 practically formed into a bell crank lever as will be understood from Fig. 3, and the lower end of this bell crank lever is pivotally connected to a rod 44 extending obliquely downwardly. There are two of these 15 rods 44. At 45 are two rails mounted upon the floor of the car and extending crosswise thereof and parallel with each other. Engaging these rails are grooved wheels 46 which support a framework 47, the latter being movable in the general direction of 20 the length of the rails 45. Connected with opposite sides of the frame work 47 are links 48 which are pivoted to levers 49, these levers being journaled in bearings 50.

25 A seat 51 is mounted upon the frame work 47 and is adapted to be occupied by the operator during the flight of the machine. When the seat 51, with the weight of the operator upon it, is moved to the right or 30 to the left according to Fig. 3, the levers 49 are shifted accordingly, one of the rods 44 being moved obliquely upward, and the other rod 44 being moved obliquely downward. The movements of these respective 35 rods tilt the bell crank levers 41, causing one of the collars 37 to be raised and the other collar 37, upon the opposite side of the machine, to be lowered. The result is that one pair of blades 39 is adjusted in one 40 direction, while the other pair of blades 39 is adjusted in the opposite direction.

The parts are so connected and geared 45 relatively to each other that the adjusting movement of the propeller blades 39 is such as to correct the position of the machine, in the sense that these propeller blades thus adjusted, tend to shift the weight of the seat 51 and of the operator sitting upon said seat back into normal position, regarding 50 had to the fact, of course, that the blades 39 have rotary motion given them by virtue of the power of the engine 23.

The standard 10^a is provided at its upper 55 end with a fork 13^a (see Fig. 6), and journaled to this fork is a swinging yoke 13^b. Extending through the fork 13^a and yoke 13^b is a shaft 52 serving as a pivot upon which the yoke 13^b is adapted to swing. Mounted rigidly upon the shaft 52 is a bevel 60 gear 53 which meshes with a bevel gear 54. Mounted integrally upon the yoke 13^b and extending upwardly therefrom is an arm 55 carrying at its outer end a pivot pin 56 65 which supports a bell crank lever 57. A weight 58 is mounted upon this bell crank

lever and hangs freely. The bell crank lever 57 is provided, opposite its end carrying the weight 58, with a forked portion which engages a collar 59. This collar encircles a shaft 60 and is movable in the general direction of the length of the latter. Links 61 are, by aid of pivot pins 62, mounted upon the collar 59. These links are also connected by pivot pins 63 with arms 64, these arms being respectively mounted rigidly upon two blades 65, these two blades constituting together a propeller. A rod 67 is, by aid of a pivot pin 66, connected with the arm 55. This rod is also pivotally connected with a hand lever 68, and this hand lever carries a pawl 69.

Adjacent the hand lever 68 and in registry with the pawl 69 is a toothed sector 70. A tiller post 71 supports a rudder 72, these parts being disposed below a supporting 85 plane 73 and being of the usual or any preferred construction.

The operator, after shifting the hand lever 68 into different angular positions, may secure said lever by aid of the pawl 69. By shifting the hand lever 68 into different positions, the arm 55, and with it the yoke 13^b, is swung into different angular positions, the result being that the shaft 60 carrying the propeller blades 65 is shifted 95 to different angles relatively to the framework of the machine. The weight 58 tends to hang directly downward independently of any inclination of the aeroplane. If, therefore, the machine is raised so that the 100 weight 58 assumes a position parallel with the axis of the shaft 60, the collar 59 is in consequence moved toward the upper end of the shaft 60 and the propeller blades 65 are, therefore, caused to assume a common 105 plane which coincides with the plane of rotation. In other words, each blade 65 now presents little, if any, angular surface to the wind, each blade edgewise cutting through the air. Suppose, however, that the machine tilts so that its forward end points 110 downwardly at an abrupt angle as compared with its horizontal position (see Fig. 2). The weight, still tending to hang vertically 115 downwardly, shifts the position of the collar 59 away from the upper end of the shaft 60. This causes the links 61 to turn the blades 65 each upon its own longitudinal axis so that the blades are inclined, as indicated in Fig. 6, the degree of inclination 120 being related to the slant of the machine and being greater as the dip of the machine is increased. The operator, by manipulating the hand lever 68, can move the arm 55 upon the shaft 52 as a center and may lock the arm 55 in any desired position within certain limits. In doing this he can, within proper limits, tilt the shaft 60 forward or backward. The weight 58 works automatically 125 in causing the blades 65 to be ad-

justed properly, yet in extreme cases the operator may, by manipulating the hand lever 68, cause the weight 58 to increase or diminish the automatic adjustment of the 5 blades 65.

From the foregoing description it will be noted that the propellers disposed upon opposite sides of the machine and comprising the propeller blades 39 are adjusted automatically by virtue of the weight of the seat 51 and the operator sitting thereupon, this weight being shifted to one side or the other by the side or lateral tilting of the machine, the adjustment of the blades 39 being such 15 as to correct the inclination of the machine and bring the seat 51 carrying the operator back to normal position. Again, if the machine dips abruptly downward, as indicated in Fig. 2, the propeller blades 65, under control of the weight 58, adjust automatically to such an extent and in such a direction as to afford a greater or lesser depressing effect on the rear end of the machine, thereby tending to correct the position of the machine 25 and to prevent a dangerous alighting thereof.

I do not limit myself to the precise type of propellers herein shown, nor to the exact arrangement disclosed for handling these 30 propellers, the scope of my invention being mentioned in my claims.

Having thus described my invention, what I claim as new and desire to secure by Letters Patent is:—

35. 1. A device of the character described comprising a framework, a propeller shaft supported thereby, a propeller mounted upon said propeller shaft, means for turning said propeller shaft in order to actuate 40 said propeller, mechanism controllable by hand for shifting said propeller shaft to different angles relatively to said framework, and means controllable by gravity for adjusting the blades of said propeller automatically.

45. 2. A device of the character described comprising a car provided with planes and adapted to be carried through the air, a propeller shaft extending from said car and movable to different angles relatively to the latter, a propeller on the shaft, an arm, for shifting said propeller shaft to different angles relatively to said car, means controllable at will for shifting said arm to different angular positions, a weight journaled upon said arm and depending from the same, and mechanism connected with said weight and controllable thereby for changing the pitch of said propeller in order to vary the power 55 thereof.

60. 3. In a flying machine, a frame-work, an adjustable propeller, intermediate of the sides of the frame-work and provided with adjustable blades, means controlled by gravity for adjusting the blades when said

frame-work dips downwardly, a propeller on each side of the frame-work and provided with adjustable blades, and mechanism controlled by gravity for adjusting the blades of one propeller in one direction and 70 those of the other in the opposite direction when the frame-work tilts laterally.

4. In a flying machine, a frame-work, a pivoted propeller shaft intermediate of the sides of the frame-work, means for shifting 75 the propeller shaft to different angles relatively to the frame-work, a propeller on the shaft and having adjustable blades, means controlled by gravity for adjusting the blades of the propeller when the frame-work 80 dips downwardly, a propeller shaft at each side of the frame-work, propellers on the shafts and having adjustable blades, and mechanism controlled by gravity for adjusting the blades of one propeller in one direction and 85 those of the other in the opposite direction when the frame-work tilts laterally.

5. In a flying machine, a frame-work, a transversely extending track on the frame-work, a seat mounted to travel on the track, a propeller shaft at each side of the frame-work, a propeller on each shaft having adjustable blades, collars slideable on the said shafts, links connecting the collars with the 90 blades of the propellers, pivoted bell crank levers each having one member engaging a collar, crank arms at opposite sides of the frame-work, links connecting the seat with the crank arms, and rods connecting the 95 crank arms with the bell crank levers.

6. In a flying machine, a frame, a shaft having a bevel gear wheel thereon, a yoke loosely mounted on the shaft, a shaft mounted in the yoke and having a bevel gear 100 wheel meshing with the gear wheel of the said shaft, a propeller on the shaft of the yoke and having pivoted blades, a collar slideable on said shaft, links connecting the 105 collar with the blades, a pivoted bell crank having one member weighted and its other member engaging the said collar, and means for swinging the said yoke.

7. In a flying machine, a frame, a pivoted yoke, means for swinging the yoke, a shaft 110 mounted in the yoke, a propeller mounted on the shaft and having pivoted blades, a collar slideable upon the shaft, links connecting the collar with the blades, and a pivoted bell crank having one member weighted and its 115 other member engaging the said collar.

8. In a flying machine, a frame, a pivoted member, pivoted vanes carried by the said member, a slideable member carried by the pivoted member, links connecting the slideable member and vanes, and a pivoted and weighted member engaging the slideable member.

9. In a flying machine, a frame, a pivoted member provided with a lateral arm, pivot- 120

ed vanes carried by the pivoted member, a
slidable member carried by the pivoted
member, links connecting the vanes with
the slidale member, a pivoted and weighted
elbow arm engaging the slidale member, a
hand lever, and a link connecting the hand
lever with the arm of said pivoted member.

In testimony whereof I have signed my
name to this specification in the presence of
two subscribing witnesses.

THOMAS M. DANIELS.
